UNITED STATES PATENT OFFICE.

RANDOLPH CROMPTON, WILLIAM E. WOODMAN, AND ROBERT J. ADAMS, OF WORCESTER, MASSACHUSETTS; SAID WOODMAN AND ADAMS ASSIGNEES TO SAID CROMPTON.

MAGAZINE FOR WEFT-REPLENISHING LOOMS.

Application filed May 26, 1919. Serial No. 299,977.

To all whom it may concern:

Be it known that we, RANDOLPH CROMPTON, WILLIAM E. WOODMAN, and ROBERT J. ADAMS, citizens of the United States, residing at Worcester, in the county of Worcester and Commonwealth of Massachusetts, have invented a new and useful Improvement in a Magazine for Weft-Replenishing Looms, of which the following, together with the accompanying drawings, is a specification.

Our invention relates to hoppers or magazines for automatic weft replenishing looms, and it has for its object to provide an improved form of magazine embodying certain novel features not heretofore provided in looms of the above described type.

In automatic weft replenishing looms, a series of filling carriers, such as bobbins or cops are carried in a rotary hopper or magazine, and suitable actuating mechanism is provided to automatically eject a filling carrier from the shuttle and to insert a fresh filling carrier therein upon the detection of filling absence by the filling detecting devices. In placing the bobbins or cops in the magazine it is most essential that each filling carrier should be held accurately in position with respect to the shuttle, and furthermore, that the filling carrier should be easily detached from the magazine when it is necessary to insert it in the shuttle.

By our invention we provide an improved form of holder for the small ends of the bobbins or cops whereby the filling carriers are held in proper position and at the same time may be readily detached from the holder. In addition our improved form of holder is capable of being quickly and easily re-placed in the magazine by reason of the fact that it is held in position without the use of rivets or screws, or other permanent fastening devices. We also provide a guard ring for preventing accidental displacement of the filling carriers.

The magazines of weft replenishing looms as heretofore constructed, have usually comprised an integrally cast sleeve and end plate for supporting the butt ends of the filling carriers, the end plate being provided with cast on ratchet teeth adapted to be engaged by suitable pawl members for advancing the magazine after each filling replenishment.

By our invention, it is proposed to im-

prove the above described arrangement by casting the sleeve and ratchet separate from the butt-end plate; and chilling the metal of the teeth in order to increase the wearing qualities thereof. This latter step has been found to be impracticable with the former integral construction owing to the fact that the plate is of considerable larger diameter than the ratchet teeth, thus making it extremely difficult to chill the teeth without spoiling the portions of the casting beyond the periphery of the teeth. We also provide a novel form of feeding pawl for engaging the ratchet teeth and advancing the hopper after filling replenishment.

In the accompanying drawings, Figure 1 is a transverse sectional view of a portion of a magazine embodying our invention.

Figure 2 is a view in front elevation of a portion of the parts shown in Fig. 1.

Figures 3 and 4 are detail views showing a portion of the parts shown in Fig. 2.

Figures 5 and 6 are views in front and side elevation respectively, showing a modification of the filling carrier holder shown in Fig. 2.

Figure 7 is an enlarged sectional view along the line 7—7, Fig. 1.

Figure 8 is a view in side elevation of a portion of the parts shown in Fig. 7.

Similar reference characters refer to similar parts in the different figures.

Referring to Fig. 1, a hopper plate 1 is supported upon the breast beam of the loom, not shown, and is provided with a longitudinally extending stud 2 upon which the hopper or magazine is rotatably mounted. A sleeve 3 surrounding the stud 2 is provided at one end with a flange 4 having a plurality of ratchet teeth 5 formed on the outer periphery thereof. The sleeve 3, the flange 4, and the teeth 5 are preferably formed in a single casting and the outer peripheral portion of the flange 4 is chilled so that the teeth 5 will present wear resisting working surfaces. A butt-end plate 6 is secured to the flange 4 by means of set screws or rivets 7, and is located within a rim 8 provided on the hopper plate 1. A small-end plate 9 is provided with a central hub portion 10 and is secured upon the other end of the sleeve 3 by means of a set screw 11. As best shown in Fig. 2, the plate 9 is provided with a cen-

tral web section 12 surrounding the hub 10, and with a plurality of arms 13 radiating therefrom for supporting a rim 14. The web section 12 is provided with a plurality of substantially circular depressions or recesses 15 that are located at the base of the spaces 16 between the arms 13.

A plurality of small-end holders 17 are arranged in the spaces 16 with their end portions extending into the seats 15. Each holder 17 is preferably formed from a single piece of wire and comprises a loop portion 18 that is located outside of the periphery of the rim 14. The sides of the loop portion 18 come together at the top and are then bent outwardly and downwardly to form legs 19 for supporting the holder. The legs 19 are bent outwardly in opposite directions at their ends to conform to the seat 20 15, as shown at 20. A clamping ring 21 is provided with a plurality of substantially circular projections 22 that are respectively adapted to be received in the seats 15 and to occupy the space not taken up by the bent out portions 20, as shown in Figs. 3 and 4. The recesses 15 and the projections 22 are so proportioned that the legs 19 are clamped tightly in position when the clamping ring 21 is secured to the plate 9 by any suitable means.

A plurality of filling carriers 23, shown here as cops, are supported at their butt-ends in depressions 24 provided in the butt-end plate 6 and with their small-ends or tips 25 respectively seated in the loops 18 of the tip holders 17. In placing a cop 23 in the hopper, the butt-end is first inserted in a depression 24 and the tip 25 is then forced downward between the converging side portions of the loop 18 until it is seated at the bottom of the loop. The cop 23 is then rigidly supported at its butt-end while its tip is yieldingly held in position and is substantially inclosed by an inherently resilient member, so that it may be readily removed from the hopper when engaged by the transerrer, in which case the tip 25 forces the sides of the loop 18 apart.

A modification in the form of the small-end holder is shown in Figs. 5 and 6 in which the small-end plate 26 is provided with an annular groove 27 and a plurality of slots 28 extending across the radial arms 29. A holder 30 is formed with a loop portion 31, the bottom of which is flared outwardly, as shown at 32, to receive the small-end of a bobbin, the sides of the loop 31 being spaced apart a distance somewhat less than the diameter of the small-end of a bobbin. The ends of the loop 31 are bent downwardly to form legs 33 that are located in the groove 27. The legs 33 are bent upwardly at the bottom of the groove 27 into parallel relation with the adjacent arms 29 and are provided at their ends with hook

portions 34 that are received in the slots 28 on opposite sides of the loop 31. The legs 33 are held in the groove 27 by means of a clamping ring 35. The modified tip holders 30 are thus adapted to receive the small ends of bobbins and to yieldingly maintain them in position in the same manner as described with reference to the tip holders 17.

The small-end plate 9 is further provided with a plurality of arms 36 projecting radially outwardly from the rim 14. The arms 36 are provided at their ends with notches 37 within which is seated a ring 38, preferably formed of resilient material, such as wire. The function of the ring 38 is to provide a guard for preventing external objects from coming into contact with the small ends of the filling carriers, and thereby disarranging them. The ring 38 is therefore made somewhat resilient so that it is capable of yielding upon receiving a heavy blow and the notches 37 are formed with their inner walls cut down, as shown at 39, to allow the ring 38 to spring out of the notches 37, if sufficient force is applied thereto.

Referring now to Figs. 7 and 8, a transfer arm 40 is pivotally mounted on a transfer stud 41 that is carried by the hopper plate 1. A coiled spring 42 surrounding the stud 41, is secured at one end to the stud 41 and at its other end to a hub 43, of the transfer arm. The spring 42 tends to move the transfer arm 40 in the direction of the ratchet teeth 5. A feeding pawl 44 is pivotally mounted on a pivot pin 45 at the free end 100 of the transfer arm 40, and is yieldingly held against a stop arm 46 on the arm 40 by means of a spring 47 secured at its ends to the arm 40 and to a lug 48 provided on the pawl 44. The pawl 44 is provided with 105 a tooth 49 that is adapted to engage the ratchet teeth 5. A stop pawl 50 is pivotally mounted at the point 51 upon the hopper plate 1 and is provided with a tooth 52 for engaging the ratchet teeth 5. The stop pawl 110 50 tends to turn about its pivot 51 under the force of gravity, in the direction of the ratchet, so that the magazine is normally prevented from turning by the engagement of the tooth 52 with the teeth 5.

Upon the operation of the filling absence detecting devices, the transfer arm 40 is moved downwardly in the direction of the filling carriers 23 and removes one of the carriers to replenish the shuttle. As the transfer arm 40 moves downwardly the feeding pawl 44 turns about its pivot against the action of the spring 47 and the tooth 49 slips over the ratchet teeth. On the upward motion of the transfer arm the feeding pawl 125 tooth 49 engages the next lowest tooth 5 of the ratchet and turns it through a distance of one tooth, the upward thrust of the transfer arm 40 being sufficient to move the stop pawl 50 upwardly about its pivot and 130

- to allow the tooth 52 to slip one ratchet tooth 5. The stop pawl 50 always prevents the hopper from turning in a counterclockwise direction to feed backward.
5. From the foregoing it is apparent that the arrangement of the ratchet and pawl devices is extremely simple and that the action of the feeding pawl and of the stop pawl in advancing the hopper the distance 10 of one tooth after filling replenishment and in preventing backward movement is obtained without the use of any auxiliary devices, such as have been heretofore employed.
- It is also apparent that the several features of our improved hopper or magazine 15 can be applied either separately or collectively to looms already in use with but a slight rearrangement of the hopper.
- We claim,
- 20 1. In a hopper or magazine for automatic looms, a small-end plate and a clamping member, and a wire member for supporting the small end of a filling carrier, the said small-end plate and the said member being provided with coacting recessed and projecting portions for holding the said member in position.
- 25 2. In a hopper or magazine for automatic looms, a small-end plate provided with a recessed portion and a resilient support for the small end of a filling carrier provided with a projection located in said recessed portion, and a member for clamping said portions together.
- 30 3. In a hopper or magazine for automatic looms, a small-end plate provided with a recess, a resilient support for the small end of a filling carrier provided with a projection conforming to said recess and partially occupying the same, and a clamping member 35 provided with a projection filling said recess for retaining said support in position.
- 35 4. In a hopper or magazine for an automatic loom, a resilient member provided with a loop for seating the small end of a filling carrier, the top portions of said loop being closer together than other portions thereof, to prevent the displacement of the end of the filling carrier.
- 40 5. In a hopper or magazine for automatic looms, a small end plate, a plurality of annularly arranged members for supporting the small ends of filling carriers beyond the periphery of said plate, and a readily un-
- seated guard member carried adjacent to the 55 said supporting members to prevent accidental displacement of filling carriers.
6. In a hopper or magazine for automatic looms, a small end plate, a plurality of annularly arranged members for supporting the small ends of filling carriers beyond the periphery of said plate, and a yieldable 60 guard ring carried beyond and adjacent to the said supporting members.
7. In a hopper or magazine for automatic 65 looms, a plurality of annularly arranged filling carriers, a small-end plate provided with a plurality of resilient members for bodily supporting the small ends of the filling carriers beyond the periphery of said 70 plate, and an annular guard member carried adjacent to said supporting members, the said guard member being adapted to be readily unseated.
8. In a hopper or magazine for an automatic loom, a resilient member provided with an elongated loop for seating the small end of a filling carrier, the side portions of the loop converging to prevent the displacement of the end of the filling carrier. 75
- 80 9. In a hopper or magazine for an automatic loom, a wire form providing a loop for supporting the small end of a filling carrier, the sides of the loop being contracted to prevent the free insertion or withdrawal 85 of the end of the filling carrier therefrom.
10. In a hopper or magazine for an automatic loom, a wire form providing a loop for seating the small end of a filling carrier, the sides of the loop being yielding to permit 90 forcible entrance of the end of a filling carrier, and being close enough together to prevent displacement of a carrier after it is received in the loop.
- 95 11. In a hopper or magazine for an automatic loom, a wire form for supporting the small-end of a filling carrier and comprising a shank terminating in a bent over loop, the sides of which are contracted to prevent the displacement of the end of a filling car- 100 rier.

Dated this seventeenth day of May, 1919.
